UNITED STATES PATENT OFFICE

2,641,176

PREPARATION OF CANNED PRODUCTS

Edward N. Higgins, Emsworth, and Vernon P. Evans, McKees Rocks, Pa., assignors to H. J. Heinz Company, Pittsburgh, Pa., a corporation of Pennsylvania

Application June 21, 1945, Serial No. 600,690

2 Claims. (Cl. 99—362)

1

This invention relates to the sterilization of canned foods and like products and is for an apparatus and method by which this operation may be continuously performed and in coordinated relation with a can closing and a labeling machine.

Many canned foods are charged into a tin can in a cooked or semi-cooked, or even raw condition, the can sealed, and then the can is heated for a prolonged period of time at a temperature, usually above the boiling temperature of 212° F. Commercially this is accomplished by charging batches of filled closed cans into an autoclave, sealing the autoclave, admitting steam to maintain the right temperature, after which they are held at sterilizing temperature for the necessary period of time. Then the autoclave must be cooled until atmospheric pressure within it is reached, after which it is opened. Much time is lost in this operation, and it is necessary to have several autoclaves to secure satisfactory continuity of operation.

According to the present invention, the containers, after being filled, are sealed. They then are carried at a predetermined rate through a bath of liquid having a boiling point substantially higher than that of water. A mineral oil having a flash point of around 300° F. for example may be used, such an oil having an even higher boiling point. The containers move slowly, but continuously, through this bath for the necessary period of time.

Moreover, according to our invention the cans may move directly from the closing machine into the sterilizing bath. From this bath they pass under a hot water spray, which removes the high boiling point fluid. This fluid according to our invention is recovered for re-use. The cans then pass in succession past detergent, cooling and air drying sprays, direct to a labeling machine so that the entire process can proceed without interruption.

Our invention may be more fully understood by reference to the accompanying drawings, in which:

Fig. 1 is a schematic view of the forward section of the processing apparatus;

Fig. 2 is a similar view of the balance of the apparatus;

Fig. 3 is a longitudinal section through a portion of the sterilization trough on a larger scale; and

Fig. 4 is a transverse section in the line IV—IV of Fig. 3.

In the drawings, A designates a can closing

2

machine of any known or preferred type in which the cans are successively filled and sealed. From this machine the filled and closed cans are transferred to a conveyor belt 2 at one end of a long narrow trough 3, by a transfer mechanism, as for example a pusher bar, not shown. The belt slopes down into the trough as indicated at 4. In the trough is a body of liquid 5 that has a boiling point substantially higher than that of water. As previously indicated, a liquid having a boiling point of at least 250° F., and preferably a mineral oil having a flash point of at least 300° F. and an even higher boiling point, is used, and the temperature of the bath is kept somewhere in the region of 250° to 300° F.

The conveyor, which may move along tracks 6 on the side walls above the bottom and which may be formed of a succession of mesh panels, carries the cans at level where they are entirely submerged. In the trough below the conveyor are steam pipes 7 to which high temperature, high pressure steam is supplied. Additionally, there are low pressure steam pipes 7a which may have small perforations therein so that a limited amount of steam at lower pressure may be discharged into the bath. The steam pipes 7a thus serve the purpose of more rapidly heating the liquid and of constantly agitating the bath to more rapidly carry the heat from the pipes 7 to the cans, while the pipes 7 provide the high temperature.

At the opposite end of the trough the conveyor slopes upwardly at 8 to the top of the trough. Beyond the discharge end of the trough the conveyor passes over another vessel 9 above which are hot water spray nozzles or pipes 10. These spray hot water onto the cans, washing off practically all adhering oil from the bath.

The hot water is collected in the vessel 9 where the oil and water separate, or the mixture of hot water and oil may be carried off to a separating means. The water and oil taken from the vessel 9 may discharge, for example, into a continuous liquid-liquid centrifuge 11, the oil discharged into vessel 11a from which it is forced by a pump 12 directly to the sterilizing bath, or as shown, to a reservoir 13. The hot water may, if desired, be reused. Beyond the vessel 9 the conveyor passes over another vessel 15 above which are arranged sprays 16 for spraying the cans with hot water and a detergent such as soap. This water is collected in the vessel 15 and may be recirculated. This operation removes the last vestige of oil from the cans. The conveyor also extends over another vessel 17 with sprays

18 above it for directing jets of cold water onto the cans to substantially cool the cans, the cold water being collected in the vessel 17 for re-use. Next the conveyor extends past a drying station where a plurality of jets or sprays 19 of air are directed against the cans for thoroughly drying them. Thereupon the conveyor discharges the cans to a labeling machine designated 20, which may be of any known or preferred construction, and which accepts the cans as fast as they are delivered to it, applying the labels thereto and discharging them in condition to be packed. A converging disk conveyor (not shown), may satisfactorily transfer the cans from the main conveyor to the labeling machine.

The trough is long enough and the liquid therein is maintained at a sufficiently high temperature to assure adequate sterilization of the contents of the can, the speed of the conveyor also being adjusted to give proper sterilization. In order to correlate these factors, the drawings illustrate a variable speed control such as a rheostat 21 for variably controlling the speed of the closing machine, rheostat 22 for adjusting the speed of the main conveyor, and rheostat or other speed control means 23 for controlling the speed of the labeling machine. 24 indicates a thermostatic control element for the high pressure steam inlet pipe so as to adjust the temperature to the time of travel of the cans through the bath and maintain a uniform high temperature in the bath, there being a thermostatically controlled valve at 24a.

It will thus be seen that our invention enables the closing, sterilizing, and labeling of the cans to progress continuously and at a predetermined rate, each unit being correlated to each other so as to avoid work stoppage which result with the intermittent processes now required through the use of pressure cookers. It has been found that the cans successfully resist the pressure generated in them in passing through the hot oil bath, and cans which are defective can frequently visibly be detected, whereas present methods of pressure cooking afford no such opportunity for inspection. By reason of the hot water spray following the removal of the cans from the hot oil bath, practically all of the oil that is carried out by the cans is removed and recovered for re-use. Any slight film that remains is effectively removed by the detergent spray while the cooling jets accelerate the cooling of the cans to a temperature where they can be safely handled and drying currents of air condition the cans for immediate application of the labels.

As illustrated in the drawings, an exhaust hood 25 may be placed over the trough, to exhaust fumes or vapors therefrom, and another hood 26 may be over the several sprays. These discharge fumes and vapors at some remote or outside space.

While we have illustrated more or less schematically one specific embodiment of our invention, it will be understood that this is by way of

illustration, and that various changes and modifications may be made in the construction and arrangement of the parts within the contemplation of our invention and under the scope of the following claims.

We claim:

1. Apparatus for continuously sterilizing sealed cans of food or the like, comprising a trough, a bath of mineral oil in said trough having a boiling point at atmospheric pressure substantially higher than the boiling point of water, a conveyor extending into and out of and along the trough below the top of the trough so that cans on the conveyor will be submerged in the bath, high pressure steam pipes immersed in the liquid in the trough for heating the liquid, and low pressure steam pipes in the liquid having holes therein for the escape of steam into the bath for agitating the bath and directly heating the liquid.

2. Apparatus for sterilizing closed food containers comprising an elongated trough, a conveyor movable along the trough below the top thereof and entering the trough at one end and emerging therefrom at the other, a bath of mineral oil in the trough, means for heating the oil to a sterilizing temperature above 212° F., said means comprising a high pressure steam coil submerged in the bath below the conveyor, and a low pressure perforated steam pipe in the bath below the conveyor for directly heating and agitating the oil, the depth of the bath above the conveyor being such as to cover containers on the conveyor.

EDWARD N. HIGGINS.
VERNON P. EVANS.
